HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

MATRIX-MAKING MACHINE.

Application filed August 6, 1925. Serial No. 48,542.

This invention is an improvement in machines for making or rolling matrices in the manufacture of stereotype plates. Said machines as ordinarily constructed have a reciprocating bed, on which is placed the type form or surface from which the matrix is to be made, and a pressure roll which cooperates with said bed to press the paper or flong for the matrix upon the face 10 of the type form so as to produce an intaglio impression in the flong from the type; considerable pressure being required to force the printing surface of the type form into the flong or paper sheets to make the matrix. 15 This pressure in such matrix machines sometimes distorts or displaces the flong or causes it to wrinkle, resulting in an imperfect matrix, and necessitating the making of another. 20 The object of the present invention is to eliminate troubles of this nature by providing means to smooth or iron the flong and press it gently against the type as and before it passes between the pressure roll and the 25 bed, whereby severe pressure is applied thereto.

I will illustrate and explain one practical embodiment of the invention as applied to a known type of matrix making machine to enable others to adopt and use the invention; and summarize in the claims the essentials of the invention and novel features of construction and novel combination of parts for which protection is desired.

In the accompanying drawings:

Figure 1 is a diagrammatic side elevation of part of a well known type of matrix rolling machine equipped with one practical embodiment of my invention; well-known parts 40 of the machine which are unnecessary to an understanding of the present invention being omitted.

Figure 2 is an end view of Figure 1.

Figures 3 and 4 are enlarged detail views 45 of the parts more particularly relating to the present invention, and illustrating the operation thereof.

The matrix machine shown is of a well-known type, and has side frames 1 between 50 which is mounted a reciprocable bed 2, having racks 2^a meshing with gears 3^a on the end of a bed supporting and operating roll

3, which is mounted on a shaft 3^b journaled in the frames 1.

Mounted above the bed and roll 3 is a 55 pressure roll 4 having a shaft 4^a, journaled in the frames 1. The rolls 3 and 4 are provided with intermeshing gears 3^c, 4^c, by which they are operated in unison.

The roll 3 may be driven by any suitable 60 mechanism, not illustrated, such as is commonly employed in such machines. The frames 1 may be connected by the usual suitable ties; only one tie bar 1^a being shown in the drawings, this bar 1^a being located 65 above the cylinder 4.

The bed 2 is adapted to carry the type form or printing surface, indicated at P, from which a matrix is to be made; such matrix being made by laying a flong or sheet 70 of prepared paper F upon the surface of the type form and then pressing the flong onto the surface of the type form by passing the bed beneath the roll 4, which forcibly presses the flong against the surface of the 75 type so that it receives an intaglio impression therefrom. Customarily one or more blankets B are laid over the flong to cushion the pressure applied by the roll 4 thereto, and to protect the flong from direct contact 80 with the roll.

All the foregoing parts may be constructed and operated as in the well known matrix roller machine and need no further explanation.

When the machine is started, the bed moves in one direction for the length of the bed and then stops. If this one stroke is all that is necessary to properly impress the flong it is removed from the type form (the bed being then in position to receive a new flong) and on the next return stroke of the bed, in the reverse direction another matrix may be rolled. Sometimes, however, it is necessary to have the bed make two or more 95 strokes in order to sufficiently or perfectly impress the type into the flong.

Considerable pressure between the roll and the form is necessary to force the printing face of the form into the flong and, as stated, in machines as ordinarily constructed this pressure sometimes distorts the flong and causes it to wrinkle, or displaces it on the form, with resultant loss of material and

time; and my invention eliminates this trouble by smoothing or ironing out the flong with a gentle pressure before it is subjected to the severe pressure of roll 4.

5 In the specific embodiment of the invention shown in the drawings, pairs of oppositely disposed members or shoes 5 and 6 are mounted upon the roll 4 adjacent the opposite ends thereof; each member of each pair extends approximately 120 degrees around the surface of the roll 4, and is concaved on its inner face to conform to the periphery of the roll 4, and the inner surfaces of the adjacent members 5 and 6 are 10 preferably provided with suitable brake linings 5^a, 6^a, adapted to engage the periphery of the roll 4. The members 5 and 6 of each pair are also preferably pivotally connected together at their upper ends and 15 are preferably pivoted on a rod 7, which connects the pair of members, and said rod is carried by the said members which are supported by the roll.

In the lower ends of the members 5 is 20 journaled a roller 5^b; and in the lower ends of the members 6 is journaled a roller 6^b; said rollers 5^b, 6^b being so disposed that if the pivot 7 is directly over the axis of the roll 4, neither roller 5^b or 6^b would be in position to contact with the flong or blanket 25 on the type form if the bed moved it thereunder.

The pairs of members 5 and 6 are properly spaced apart by means of collars 7^a on rod 7 30 and the rolls 5^b, 6^b and the lower ends of the members are restrained by collars 5^d and 6^d on the shafts of the rollers, as indicated in the drawings, or in any other suitable manner. The rod 7 members 5 and 6 and rollers 40 5^b, 6^b being mounted on the roll 4 as described will move bodily with the roll 4 when the same turns to the right or left until their movement is arrested by proper stop means.

As shown members 5 and 6 are provided 45 with upwardly projecting lugs 5^e and 6^e, respectively, which are adapted to contact with opposite side of the tie bar 1^a and limit the rotatorial movement of the pairs of members 5 and 6 and rollers 5^b, 6^b with and 50 around the roll 4.

The members 5 and 6 are caused to yieldingly clamp the cylinder 4 between them by means of an extension spring 8 interposed between the lugs 5^e, 6^e. Said spring may be 55 strung upon a rod 8^a pivotally connected with one of the lugs and extending through the other lug as indicated in Figures 3 and 4.

Operation.

60 A form of type or printing surface from which the matrix is to be made is placed on the bed 2 when the latter is at the end of its outward movement at either end of the main frame. The flong or paper F for 65 the matrix is laid over the type form, and

one or more blankets B placed over the flong. The machine is then started so as to, for example, turn the roll 4 clockwise and move the bed 2 to the left (as in Fig. 3). As roll 4 starts to revolve the members 5 and 6 which are supported thereon turn clockwise with the roll until the rotatorial movement of said members is arrested by the lugs 5^e engaging the bar 1^a, or by other suitable stop means. This movement of the members 70 brings the roller 6^b into position to engage the blankets and flong, as the bed passes to to the left, and press the flong against the form with a pressure determined by the extent of frictional pressure between the members 5 and 6 and the surface of the roll 4. The roller 6^b thus presses and holds the flong lightly but smoothly against the type form and prevents shifting or buckling of the flong in advance of the severe pressure 80 applied to the flong by roll 4. The aforesaid initial movement of the members 5 and 6 while lowering the roller 6^b to operative 85 position, raises the roller 5^b so that it will not contact with the flong or blankets as they 90 pass out from beneath the roll 4 (see Figure 3).

When the bed has completed its stroke to the left the machine stops and is ready for 95 operation in the reverse direction. The impressed matrix can be removed from the type form, and if it is desired to make another matrix from the same type form a fresh flong is placed upon the type and the machine operated to move the bed to the 100 right (Figure 4). As the bed starts to the right the roll 4 revolves anti-clockwise and members 5 and 6 turn with the roll until their movement is arrested by the lugs 6^e engaging the bar 1^a; and this movement lowers 105 the roller 5^b into position to contact with the flong and smooth and press it lightly against the type surface before the flong is engaged by roll 4. When roller 5^b is lowered to operative position, roller 6^b is simultaneously 110 raised out of the way as shown in Figure 4.

Thus at each operation of the machine, or each linear movement of the bed, the flong will be lightly pressed and smoothed out before, and in readiness for, the application of 115 the severe pressure, before such severe pressure is applied thereto.

Obviously the invention is not limited to the particular construction of parts shown and described; the essentially novel feature 120 of the invention being the provision of means whereby the flong will be automatically preliminarily ironed, pressed or smoothed out before it is subjected to the severe pressure required to properly impress 125 the flong by the type.

I claim:

1. In a matrix making machine, means for 130 pressing the flong upon a type form to receive an intaglio impression therefrom; with

- means for smoothing the flong upon the type form in advance of the application of the impression pressure thereto and frictional means for applying pressure to the said smoothing means, during the operation thereof.
2. In a matrix making machine, roller means for pressing the flong upon a type form to receive an intaglio impression therefrom, with means actuated by frictional contact with the roll for lightly pressing the flong upon the type form in advance of the application of the impression pressure thereto.
- 15 3. In a matrix machine, pressure means, and means at each side of the pressure means for smoothing the flong before the application of the pressure means, and means for alternately moving the rollers into or out of operative position in accordance with the direction of rotation of the roll.
- 20 4. In a matrix machine, in combination with pressure means; of rollers disposed at opposite sides of the pressure means and respectively adapted to smooth the flong in advance of the operation of said pressure means and means for moving the rollers into or out of operative position in accordance with the direction of rotation of the roll.
- 25 5. In a matrix roller; a bed and a pressure roll coacting therewith; with means for smoothing out the flong in advance of its passage between said roll and bed and frictional means for applying pressure to the said smoothing means during the operation thereof.
- 30 6. In a matrix roller machine, a reciprocatory bed and coacting pressure roll; and means beside the pressure roll and actuated by frictional contact therewith adapted to smooth out the flong in advance of its passage between the pressure roll and bed.
- 35 7. In a matrix roller machine, a reciprocatory bed and coacting pressure roll; a roller beside the pressure roll adapted to smooth out the flong in advance of its passage between the pressure roll and bed; and means for shifting said roller into and out of operative position, in accordance with the direction of movement of the bed.
- 40 8. In a matrix roller, a bed and a pressure roll; means at each side of the roll for smoothing the flong in advance of its passage between the pressure roll and bed; and means for moving said smoothing means into and out of operative position in accordance with the direction of rotation of the roll.
- 45 9. In a matrix roller, a bed and a pressure roll; and a roller at each side of the roll for smoothing the flong in advance of its passage between the pressure roll and bed, and means for moving the opposite rollers in and out of operative position in accordance with the direction of rotation of the roll.
- 50 10. In a matrix roller, having a bed and a pressure roll; means at each side of the roll for smoothing the flong in advance of its passage between the pressure roll and bed; and means for shifting said means into and out of operative position in accordance with the direction of movement of the bed.
- 55 11. In a matrix roller, having a reciprocatory bed and coacting pressure roll; rollers disposed at opposite sides of the pressure roll and respectively adapted to smooth the flong in advance of its passage between the pressure roller and bed in either direction, and means for moving the opposite rollers in and out of operative position in accordance with the direction of rotation of the rolls.
- 60 12. In a matrix roller having a reciprocatory bed and coacting pressure roll; of rollers disposed at opposite sides of the pressure roll and respectively adapted to smooth the flong in advance of its passage between the pressure roller and bed in either direction; and means for automatically shifting said rollers into and out of operative position in accordance with the direction of the movement of the bed or rotation of the pressure roller.
- 65 13. In a matrix machine having a pressure roll; a roller beside the pressure roll adapted to smooth out the flong in advance of its passage under the pressure roller, a member supporting said roller, and means whereby said member is actuated to raise or lower the roller according to the direction of rotation of the roll.
- 70 14. In a matrix roller machine the combination of a reciprocatory bed, a pressure roll coacting therewith, a pair of members beside said roll and a pressure roller mounted on said members and movable therewith, and adapted to smooth out the flong in advance of its passage between the pressure roll and bed, and means whereby said members are raised or lowered according to the direction of rotation of the roll.
- 75 15. A matrix roller having a bed, and a pressure roll; with pairs of members beside the pressure roll, rollers mounted in said members at opposite sides of the roll, and means whereby the said members are shifted to bring the rollers into or out of operative position in accordance with the direction of rotation of the roll.
- 80 16. In a matrix machine having a pressure roll; a roller beside the pressure roll adapted to smooth out the flong in advance of its passage under the pressure roller, a member supporting said roller, and means whereby said member is frictionally supported by said roll and adapted to be raised or lowered according to the direction of rotation of the roll, and means for limiting the rotatorial movement of said member.
- 85 17. In a matrix roller machine the combination of a reciprocatory bed, a pressure roll coacting therewith, a pair of members

mounted upon said roll and frictionally engaged therewith, a pressure roller mounted on said members and movable therewith and adapted to smooth out the flong in advance of its passage between the pressure roll and bed, and means for limiting the rotatorial movement of the members with the roll.

18. In a matrix roller, a bed, a pressure roll, pairs of pivotal brackets mounted upon the pressure roll and frictionally engaged therewith, rollers mounted in said brackets carried by said members at opposite sides of the roll, and means for limiting the rotatorial movement of said members with the roll.

19. In a matrix roller machine, a reciprocating bed and coacting pressure roll; pairs of pivotal members mounted on the roll, means frictionally engaging said members with the roll to cause them to turn therewith, means for limiting the rotatorial movement of said members with said roll and rollers mounted on said members at opposite sides of the pressure roll and respectively adapted to smooth the flong in advance of its passage between the pressure roll and bed.

In testimony that I claim the foregoing as my own, I affix my signature.

HENRY F. BECHMAN.
